UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

TRAFFIC-CONTROL SYSTEM FOR RADIO BROADCAST DISTRIBUTION.

Application filed April 17, 1925. Serial No. 23,880.

My invention relates to radio broadcast distribution systems and more particularly to traffic control in such systems and has for its object the provision of a combined 5 telephone exchange system and radio broadcast distributing system with means controlled from subscribers' stations for automatically differentiating between the two kinds of service.

10 In my copending applications, Serial No. 754,460, filed December 6, 1924, and Serial No. 10,533, filed February 20, 1925, are disclosed combined telephone and broadcast service systems in which a subscriber may 15 effect different signal indications at the central office for indicating respectively the different kinds of service wanted, the differentiation between signals being made at the central office by human intelligence. 20 The present invention is directed to this provision at the central office of circuit closing means differentially responsive to different signals sent from a subscriber's station for automatically differentiating between 25 the kinds of service connection to be made with the subscriber's line.

The invention is illustrated in the accompanying drawing, which is a diagram showing the necessary apparatus and operations 30 of the circuit closing means at the central station and the differential controlling means at the subscriber's station.

Referring to the drawing in detail, C represents the central station, and S a subscriber's station connected with the central station over line wires 1—2, the vertical dotted lines indicating the distance between the stations. At the central station, are differentiating line relays TR and BR, the 40 relay TR being the telephone line relay, and BR a broadcast service line relay. The telephone service relay TR is arranged, as usual, to respond to a closure of the line circuit and close a normally open contact 3 in turn controlling the usual telephone line 45 signal or line switching apparatus, not shown, through the telephone control circuit TC which with a pair of telephone service line multiples TM, leads to the telephone 50 switchboard, not shown. Similarly, the broadcast service line, relay BR operates upon energization to close its normally open contact 4 controlling a broadcast service control circuit BC which with a pair of broadcast service, line multiples BM leads to a

radio service switchboard or switching device not shown, but which may be of any suitable type having means for connecting a source of broadcast matter with the multiples BM and having signaling or switching means controlled over the control circuit BC, such for example, as the broadcast service switching apparatus disclosed in the copending applications above referred to. To render the broadcast service relay BR 60 responsive only to a characteristic condition produced at the subscriber's station, it is made in the form of a harmonic relay with a reed supported armature 5 responsive to a periodic variation of current in the windings of the relay magnet and not responsive to a steady flow of current. Both line relays TR and BR connect with the line through normally closed contacts, of the usual cut-off relay, controlled in the usual 70 manner through the test thimbles or sleeves of the associated line jacks as well understood by those skilled in the art.

At the subscriber's substation S are provided the usual transmitter T, receiver R, 80 switchhook H, ringer Q, condenser E and induction or booster coil I having the primary and secondary windings p and s, respectively. These apparatus elements are connected according to standard practice, 85 that is, the ringer Q is normally connected across the line 1—2 in series with the condenser E, while the switchhook contacts are arranged, upon the raising of the receiver from the switchhook, to connect the 90 primary winding p and transmitter T in series across the line and connect the receiver R in a local series circuit with the secondary s, condenser E and transmitter T. Also at the subscriber's substation is 95 a broadcast receiving set BS arranged as an extension set connected to the telephone set through conductors 6, 7 and 28. This broadcast receiving set consists of a loud speaker unit 9, shunted transmitter 10, and 100 a starting button 11. The starting button being arranged upon actuation to connect the loud speaker unit and the shunted transmitter with the line through the coil I and condenser E in place of the receiver R and transmitter T, respectively, as connected by the switchhook. Thus upon actuation of the starting button 11, the shunted transmitter 10 and primary coil p are connected in series 105 across the line while the loud speaker unit 110

9, secondary winding *s*, condenser *E* and shunted transmitter 10 are connected in a local series circuit. To operatively connect the transmitter 10 in circuit the shunt switch 12 is opened, and by so doing, telephone communication may be had from the extension set.

To produce a periodic variation of current flow in the line, the subscriber's station 10 is provided with an interrupter 13, preferably of the harmonic or tuned reed type capable of operating at a given periodicity, which is arranged to be connected across the line through a normally open key or push button 14 by way of conductors 15-16. This push button is preferably situated near the extension set BS and to enable this to be done with a minimum number of extension leads from the main telephone set, the conductors 15-16 may be connected to the binding posts 17-18 instead of directly to the line conductors 1-2, which would include the primary winding *p* in circuit but with no detrimental effect on the operation of the system.

In operation, a subscriber at substation S desiring a telephone connection, raises his receiver *R* off the switchhook *H* which, as in standard practice, closes his line circuit 30 and energizes his telephone line relay *TR* at the central station. The energizing circuit of relay *TR* may be traced from the common battery *B* through circuit elements *TR*, 1, *p*, *H*, *T*, 2 and back to battery *B*. Energization of the relay *TR* closes its contact 3 which closes a telephone control circuit *TC* leading to the telephone switchboard for the purpose of controlling the usual line signal or line switch not shown, in response to the proper and usual functioning of which the subscriber's line 1-2 is connected with the telephone switchboard through telephone multiples *TM*, the line relays *TR* and *BR* disconnected from the line through the actuation of the cut-off relay and the line supplied with current through suitable battery feed devices not shown, all in accordance with known telephone practice as understood by those skilled in the art. The telephone set at the substation *S* is then connected for telephone conversation over the line, the transmitter *T* and primary winding *p* of the booster coil *I* being connected in series across the line 55 1-2 through the contacts of switchhook *H*, while the receiver *R* is connected in a local series circuit including a secondary coil *s*, condenser *E*, transmitter *T* and contacts of switchhook *H*. At the end of the telephone conversation, the subscriber hanging up the receiver opens the line circuit at the switchhook contacts, clearing his line in the manner usual in telephone practice.

When the subscriber at substation *S* desires broadcast service, he actuates key 14

to close its contacts which closes the energizing circuit of the harmonic electromagnetic vibrator 13 and causes a harmonic intermittent current to flow over the line through the broadcast service relay *BR* the path of 70 which intermittent current may be traced from battery *B'* through circuit elements *BR*, 1, 15, 14, 13, 16, 2 and back to battery *B'*. The battery *B'* may be identically the same as that indicated at *B* or a separate battery 75 balanced against the battery *B*. As the relay *BR* is a harmonic relay arranged to respond to the given periodicity at which interrupter 13 operates, it causes the armature 5 to vibrate and maintain the contact 80 4 closed, in a manner that will be understood by those skilled in the art, which closes the broadcast service control circuit *BC* leading to and controlling line signaling or switching apparatus at the broadcast distributing switchboard. This causes the subscriber's line 1-2 to be connected through the broadcast multiples *BM* to a source of broadcast supply not shown, and also causes the relays *BR* and *TR* to be disconnected 90 from the line through the operation of a suitably arranged cut off relay not shown but which may be like that shown and described in the copending applications above referred to. Upon becoming so connected, the subscriber may connect his broadcast receiving set *BS* by actuating the button 11. This connects the primary winding *p* of the induction coil *I* across the line by way of circuit elements 1, *p*, 7, 20, 21, 12, 6, and 100 2, so that broadcast matter coming over the line 1-2 is induced in the secondary winding *s* and operates the loud speaker unit 9 in the local series circuit including the elements *s*, 8, 9, 21, 12, 6, 2 and *E*. When the 105 subscriber desires to discontinue the broadcast service, he releases the starting button 11 to open the contacts 20 and 21 which opens the line circuit 1-2 resulting in a disconnection of the source of supply of 110 broadcast matter from the line at the broadcast distributing switchboard through means responsive to a prolonged opening of the line circuit after service connection, as disclosed in my copending applications above 115 referred to.

It will be understood that the cut-off relay heretofore referred to cuts off both relays *TR* and *BR* when the line is in use for either telephone or broadcast service. The 120 switching apparatus connected to line multiples *TM* and *BM* may in either or both cases be of the automatic type and to operate the same the usual dial circuit breaker or the equivalent will be provided at the subscriber's station, as disclosed in the application hereinbefore referred to. The loud speaker and its associated broadcast receiving apparatus constitute a unit, of which the periodic interrupter 13 and the key 14 are parts, sep- 130

arate from the telephone. The circuit connections of these parts 13 and 14 may then be varied specifically as described for convenience, so long as the effect is to bridge them across the line in calling as shown. For example they may be included in the telephone transmitter bridge, which would bring them across the terminals 17-18 in effect, without departing from the principles 10 of the circuit shown.

What I claim is:

1. In a combined common battery telephone exchange system and broadcast distributing system having a central station and 15 subscribers' stations connected therewith over wired lines, both systems operating within the range of audio frequencies with a telephone set and a broadcast receiver at each subscriber's station and a telephone switch- 20 board and a broadcast distributing switchboard at the central station for furnishing the subscribers with telephone and broadcast service over their respective wired lines; the combination of automatic differential 25 traffic control means comprising a telephone line relay and a broadcast service line relay individually associated with each subscriber's line and each controlling circuit leading to said telephone and to said broadcast 30 distributing switchboards respectively, and separate means at each subscriber's station associated with the telephone set and with the broadcast receiving set respectively for 35 differentially controlling the energization of said associated relays, the telephone receiver of the telephone set, and the telephone receiver or loud speaker of the broadcast receiving set being interchangeably connected to the line through the same circuit elements, 40 and being equally responsive to all audio frequency waves coming over the line.

2. In a combined common battery telephone exchange system and broadcast distributing system having a central station and 45 subscribers' stations connected therewith over wired lines both systems operating within the range of audio frequencies with a telephone set and a broadcast receiver at each subscriber's station, and a telephone switch- 50 board and broadcast distributing switchboard at the central station for furnishing the subscribers with telephone and broadcast service over their respective wired lines; the combination of a line identifying circuit 55 at the telephone switchboard for each line, a line identifying circuit at the broadcast distributing switchboard for each line, and separate means at each subscriber's station associated with the telephone set and with 60 the broadcast receiving set respectively for selectively causing the energization of said different line identifying circuits, the telephone receiver of the telephone set, and the telephone receiver or loud speaker of the 65 broadcast receiving set being interchange-

ably connected to the line through the same circuit elements, and being equally responsive to all audio frequency waves coming over the line.

3. In a combined telephone exchange system and broadcast distributing system having a central station and subscribers' stations connected therewith over wired lines, both systems operating within the range of audio frequencies, with a telephone switch- 70 board and a broadcast distributing switchboard at the central station for furnishing the subscriber's with telephone and with broadcast service respectively over their respective wired lines; the combination of a telephone service relay and a broadcast service relay at the central station individually associated with a subscriber's line, a telephone set and a broadcast receiving set at each subscriber's station, and a pair 75 of controlling means at the subscriber's station, one for each relay associated with said sets and each operable in the use of its set to effect an actuation of its associated relay only the telephone receiver of the telephone 80 set, and the telephone receiver or loud speaker of the broadcast receiving set being interchangeably connected to the line through the same circuit elements, and being equally responsive to all audio frequency waves 85 coming over the line.

4. In a combined telephone exchange and broadcast distributing system, a central station containing a telephone switchboard and a broadcast distributing switchboard, and a 100 subscriber's station containing a telephone set for conversational purposes and a broadcast receiving set, each comprising a receiver and a transmitter of standard type and both adapted to be connected to line through the 105 same induction coil and circuit connections therefor, means to supply broadcast programs through the broadcasting switchboard at audio frequencies, a pair of differential relays at the central station for each line, 110 one responsive to continuous currents over the line and of standard type to control signal circuits to the telephone switchboard, and the other responsive to variable signaling currents only and controlling signaling 115 circuits to the broadcast service switchboard, switching and signaling means at the subscriber's station for the telephone set and separate switching and signaling means for the broadcast receiving set, each adapted to 120 connect its associated set with the line and to affect the appropriate relay at the central station to produce a telephone signal or a broadcast service signal at will.

5. In a combined telephone exchange and broadcast service system, a central station and a subscriber's station and line wires interconnecting them, a telephone switchboard and a broadcast switchboard at the central station with line multiples connecting the 125 130

line with each of them, and a combined telephone and broadcast receiver at the subscriber's station comprising a telephone transmitter and a booster coil adapted to be connected across the line with the telephone receiver in the secondary circuit of the booster coil for telephonic communication, and a broadcast receiver or loud speaker adapted to be connected in the secondary circuit of said booster coil across the same terminal connections as the telephone receiver, together with variable signaling devices, one adapted to produce a steady current signal for the telephone switchboard only, the other adapted to produce a variable current signal for the broadcast service switchboard only, whereby the entire system may be operated within the range of audio frequencies, without confusion of signals and without disabling the telephone subscriber's station at any time for telephonic communication.

6. In a combined telephone exchange and radio broadcast service system, a central sta-

tion and subscribers' stations and line wires interconnecting them, means at said central station for effecting connection for telephonic intercommunication between the subscribers' lines, means also at the central station for supplying broadcast service to the subscribers' lines within the range of audio frequencies, means at the subscriber's station to receive and transmit telephonic currents for intercommunicating purposes, and other means for receiving audio frequency broadcast currents, a booster coil and talking condenser common to the telephone set and to the broadcast service, and switching means and signaling devices associated with the telephone set and the broadcast receiver respectively, adapted to differentially control signaling circuits at the central office to determine selectively the character of the service desired.

In testimony whereof I hereunto affix my signature.

EDWARD E. CLEMENT.
